UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

ROLLING-MILL.

SPECIFICATION forming part of Letters Patent No. 760,858, dated May 24, 1904.

Application filed July 9, 1901. Serial No. 67,617. (No model.)

To all whom it may concern:

Be it known that I, VICTOR E. EDWARDS, a citizen of the United States, residing in Worcester, in the county of Worcester and 5 Commonwealth of Massachusetts, have invented a new and useful Improvement in Rolling-Mills, of which the following is a specification, accompanied by drawings forming a part of the same, in which—

10 Figure 1 represents a diagrammatic plan view of a rolling-mill embodying my invention. Fig. 2 is a sectional view on line 2 2, Fig. 1. Fig. 3 is a sectional view on line 3 3, Fig. 1. Fig. 4 is a plan view, on a larger 15 scale, of a portion of the repeater by which a rod or bar is conducted from the rolls of the roughing-mill to the rolls of the finishing-mill. Fig. 5 is a section on line 5 5, Fig. 4. Fig. 6 is a section on line 6 6, Fig. 4. Fig. 7 is a section on line 7 7, Fig. 4. Figs. 8, 9, 10, 11, 12, 13 are diagrammatic views showing the movement of the rod around the curved 20 section of the repeater leading from the roughing-mill to the finishing mill. Fig. 14 is a plan view, on a larger scale, of the ends of the repeaters in front of and beneath the rolls of the finishing-mill. Fig. 15 is a longitudinal 25 sectional view of a portion of the repeater, showing a side elevation of the device for throwing the rod or bar out of the repeater. Fig. 16 is a transverse sectional view of the repeater on line 16 16, Fig. 14. Fig. 17 is a transverse sectional view of the repeater on line 17 17, Fig. 14.

30 Similar reference-figures refer to similar parts in the different views.

The object of my present invention is to provide a system of improved repeaters and devices for controlling the movement of a rod 35 or bar in its passage from a roughing-mill and continuously through the successive rolls of a finishing-mill; and it consists in the novel construction and arrangement of the repeaters and of the various rod-controlling devices, as 40 hereinafter described, and pointed out in the annexed claims.

Referring to Fig. 1 of the drawings, 1 1 denote rolls of a roughing-mill, and 2, 3, 4, 5, 6,

and 7 the successive pairs of rolls of a finishing-mill, which are located in a depression 8 below the floor of the mill of sufficient depth to bring the passes between the upper and lower rolls 9 and 10, Fig. 2, slightly below the level of the floor 11 11 of the mill in order to bring the passes between the rolls into alignment with the troughs or repeaters by which the rod is conducted successively through the rolls of the finishing-mill. Extending upon each side of the depression 8 is a metal floor 11 11, within which and below its surface are formed a series of grooves or repeaters, a repeater 12 serving for the guidance of the bar or rod from the rolls 1 1 of the roughing-mill to the first pair of rolls 2 of the finishing-mill, and from the rolls 2 a repeater 13 conducts 60 the rod to the rolls 3, and from the rolls 3 the rod is conducted by a repeater 14 to the rolls 4, and from the rolls 4 by a repeater 15 to the rolls 5, and from the rolls 5 by a repeater 16 to the rolls 6, and from the rolls 6 by a repeater 17 to the rolls 7, from which it is delivered through a trough 18.

The repeater 12 consists of a straight section 19, through which the bar is conducted from the rolls of the roughing-mill, a curved section 20, by which the direction of the bar is changed, and a straight section 21, through which the bar is conducted to the first pair of rolls 2 of the finishing-mill.

The straight sections 19 and 21 are slightly 80 wider at the bottom than at the top of the trough, as shown in Fig. 7, with the outer walls 22 flush with the floor of the mill and the inner walls 23 lower than the outer walls and connected by a floor or platform 24, flush 85 with the inner walls 23. The section 20 is curved with a constantly-decreasing radius from the receiving-section 19 to the delivery-section 21, by which the advancing end of the bar is continually subjected to a bending 90 strain as it passes around the curved section 20 of the repeater, and thereby caused to hug the outer wall 22. The outer wall 22 of the curved section is preferably undercut, while the inner wall 23 of the curved section slopes 95 upward from the bottom 25 of the trough to the

central platform or floor 24 to enable the loop formed in the curved section to be drawn out of the trough upon the floor 24. At that part of the curved section having the least radius 5 the entire inner wall 23 of the trough slopes from the bottom 25 to the floor or platform 24, with the sloping portion of the wall gradually decreasing in width as it approaches the straight sections 19 and 21. The rod in passing 10 around the repeater 12 assumes the position as shown in the diagrammatical views Figs. 8 to 13, inclusive. As the bar 26 enters the curved section its advancing end 27 strikes against the outer wall of the repeater, thereby 15 producing a bend 28 over the inner wall of the repeater at the point 29; said inner wall at this point acting as a fulcrum. The continued movement of the bar 26 causes its advancing end to slide around the inner wall into 20 the position shown in Fig. 9, when the resistance offered to the advancing end 27 by the curved outer wall will crowd the rod against the outer wall, as shown in Fig. 10, causing 25 it to hug the outer wall around the curve, as shown in Figs. 11 and 12.

When the advancing end has been engaged by the first pair of rolls 2 in the finishing-mill, the loop formed in the curved section of the repeater will be drawn over the sloping 30 inner wall upon the depressed floor 24, caused by the taking up of the rod by the rolls 2 in advance of its delivery by the rolls 1, thereby shortening the loop, as shown by the broken lines 30 and 31, Fig. 13. The depressed floor 35 24 provides a support for the loop, which is restrained between the higher outer walls 22 22 of the repeater.

The straight delivery-section 21 of the repeater 19 is provided with an enlargement or 40 gap 32, preferably provided with beveled sides 33 to enable an attendant to turn the rod to properly present it to the circumferential groove or pass of the rolls 2, to which it is conducted between suitable guides and 45 through a conveyer-trough 34. The bar as it is delivered from the rolls 2 is received in a conveyer-trough 35 and delivered to a semi-circular repeater 13, by which it is conducted to the pair of rolls 3. The repeater 13 is 50 provided with an enlarged space 36 to allow the advancing end to be turned in order to properly present it to the groove or pass of the rolls 3, to which it is conducted between suitable guides in the trough 37. From the rolls 55 3 the bar is conducted through a conveyer-trough 38 and curved repeater 14 to the rolls 4.

The repeater 14 crosses the straight section 21 of the repeater 12 at a lower level, which brings the bottom of the repeater 14 far 60 enough below the straight section 21 to allow the bar to pass through the repeater 14 beneath a bar contained in the section 21 of the repeater 12. The bar after passing the rolls 4 is conducted through a curved repeater to 65 the rolls 5 and from the rolls 5 through a

curved repeater 16 to the rolls 6. The repeater 16, like the repeater 14, crosses the repeater 12 at a lower level, and from the rolls 6 the rod is conducted through the curved repeater 17 to the last pair of rolls 7.

The troughs through which the bar is conducted to each of the rolls of the finishing-mill and through which it is delivered from the rolls is partially shown on a larger scale in Fig. 14, said figure showing a bar held in 75 the troughs. The trough 34 is provided near its mouth or delivery end with notches 39 in its opposite side walls, adapted to receive the flanged ends 40 of movable wings 41, whose free ends 42 are capable of adjustment toward 80 or away from the bar 43 by means of adjusting-screws 44, held in the side walls of the guide 34 and bearing against the wings 41 to press them toward the bar, and by screws 45, which are held in the wings 41 and carry nuts 85 46, bearing against the outside of the trough for the purpose of holding the wings 41 against the adjusting-screws 44.

The adjustment of the wings 41 enables bars of different sizes to be brought into proper 90 alinement with guide-plates 47, between which the bar is delivered to the circumferential groove 48 of the rolls. The entrance of the trough 35 is provided with a removable bearing-piece 49, against which the bar 43 is held 95 by an adjustable guide-plate 50, arranged to press against the opposite side of the bar and adjusted in a manner similar to the wing-pieces 41 by means of the screws 51 and 52.

Arranged in a recess or opening in the bottom of the trough 35 is a lifting-plate 53, carried upon the spindle 54, to which is attached a crank-handle 55 in order to rotate the plate 53 and lift the bar 43 out of the trough 35 when the advancing bend of the bar has been 105 caught in the next successive pair of rolls. The purpose of lifting the bar out of the trough is to prevent the short kinking or bending of the bar caused by the delivery of the bar at a faster speed than it is taken up by the next 110 succeeding pair of rolls. As the bar is lifted by the plate 53 its continued movement forms a loop entirely free from the trough 35 and supported upon the table 11 outside of and beyond the repeater 13, and in the same manner the bar as delivered from the rolls 4 and 6 when its advancing end has been caught by the rolls 5 and 7 is thrown out of the conveyers 15 and 17 by similar lifting-plates 53, forming 115 loops which are supported on the floor 11. The 120 curved repeaters are provided at intervals with overhanging plates 56, flush with the inner wall of the repeater and projecting over its outer wall, with the free ends 57 of the plate raised above the floor 11 high enough to permit the passage of the bar from the repeaters upon the floor 11, each of the plates 56 forming 125 a bridge over its respective repeater by which the loops as they increase or expand in radius are supported as they pass over the 130

next outward repeater. The looped bar formed from the repeater 13 as it is expanded or increased in size slides over the plates 56 of the repeater 15, and the looped bar in like manner slides over the plates 56 of the repeater 17. The floor 11 between the repeaters is flush with both the outer and inner walls of the repeaters, and as the inner walls of the repeaters are higher than their outer walls each section of floor between the repeaters is slightly inclined, as shown in sectional view in Fig. 2.

What I claim as my invention, and desire to secure by Letters Patent, is—

15 1. In a rolling-mill, the combination with a series of pairs of rolls for the continued reduction of a rod and arranged in horizontal alinement, of a series of curved repeaters connecting the successive pairs of rolls and arranged in a series of concentric curves of increasing radius as the reduction of the rod progresses, substantially as described.

2. In a rolling-mill, the combination of two successive pairs of rolls for the consecutive reduction of a rod, of a repeater between said pairs of rolls, said repeater having a curved section with its inner wall higher than its outer wall and a rod-supporting floor adjacent to said curved section and at different levels and flush with said outer and inner walls, substantially as described.

3. In a rolling-mill, the combination with successive pairs of rolls for the consecutive reduction of a rod, of a curved repeater for conducting a rod from one pair of rolls to the next consecutive pair, said repeater having an enlarged space to enable the rod to be turned to bring it into alinement with the grooves in the rolls, substantially as described.

40 4. In a rolling-mill, the combination with two successive pairs of rolls for the consecutive reduction of a rod, of a repeater between said pairs of rolls, said repeater having a curved section with its inner wall higher than its outer wall, a rod-supporting floor adjacent to said curved section and at different levels and flush with said outer and inner walls, and a bridge-plate extending from the top of the inner wall of said curved section across said repeater and over said inner wall of the curved section, substantially as described.

5. The combination with two successive pairs of rolls of a rolling-mill, of a curved repeater between said pairs of rolls, an adjacent rod-supporting floor, and means for raising a section of a rod held in said repeater above the walls of the repeater whereby the continued delivery of the rod from the first pair of rolls faster than it is taken up by the second pair of rolls will cause a loop to be formed on said floor, substantially as described.

6. In a rolling-mill comprising two consecutive pairs of rolls, the combination with said rolls, of a repeater by which a rod is conducted from one pair of rolls to the next consecutive

pair, a rocking plate and means for rocking said plate to lift the rod held in the repeater, substantially as described.

7. In a rolling-mill comprising two consecutive pairs of rolls, the combination with said rolls, of a repeater by which a rod is conducted from one pair of rolls to the next succeeding pair, said repeater having an opening in its bottom, a rocking plate pivoted in said opening and having a lever-handle by which said plate is rocked to lift the rod held in the repeater, substantially as described.

8. The combination with a pair of rolls of a rolling-mill, and a guide-trough by which a rod is supported as it enters said rolls, a movable wing connected at one end with said supporting-trough, whereby it is held from endwise movement but with its free end capable of adjustment toward or away from the rod, and means for adjusting said wing, substantially as described.

9. The combination with a pair of rolls of a rolling-mill, of a trough for supporting a rod as it enters said rolls, a pair of opposing wings each connected at one end with said trough, whereby it is held from endwise movement and adjusting-screws held by said trough by which the free ends of said wings are adjusted toward or away from a rod held in said trough, substantially as described.

10. The combination with a pair of delivery-rolls and a pair of receiving-rolls for the continued reduction of a rod, of a repeater by which a rod is conducted from said delivery-rolls to said pair of receiving-rolls, said repeater consisting of a straight receiving-section and a straight delivery-section, said straight sections being connected by a curved section having a decreasing radius from said receiving to said delivery section, substantially as described.

11. In a rolling-mill, a repeater having straight receiving and delivering sections and a connecting curved section, said curved section having an inclined inner wall to allow a rod to be drawn out of said curved section and a floor flush with said inner wall, substantially as described.

12. In a rolling-mill repeater having straight receiving and delivering sections and a connecting curved section, the combination of an outer wall, an inner wall of less height than the outer wall and a floor flush with said inner wall, substantially as described.

13. A repeater having straight receiving and delivering sections and a connecting curved section with the outer wall of said curved section undercut and the inner wall sloping and a floor flush with said outer wall and inner wall, substantially as described.

Dated this 6th day of July, 1901.
